PUSH-BUTTON MULTIPLE SWITCH

Pierre P. Pattyn, Detroit, Mich., assignor, by
mesne assignments, to Eugene Morasco

Application April 18, 1950, Serial No. 156,520

1 Claim. (Cl. 200—8)

1

This invention relates to a push-button multiple switch for lamps.

An object of this invention is to provide a push-button multiple switch structure designed for table lamps or the like which is so constructed and arranged as to provide for breaking the circuit between pairs of contacts, so that where a triple filament bulb is used the circuit will be broken between the lighting of each filament. In this manner it is not necessary in turning the switch to an "off" position to turn the switch through the complete cycle as is usual with multiple switches used with "three-way" lamps.

Another object of this invention is to provide a push-button multiple switch of this kind in which the operating button is loosely carried by the base and can be rotated in either direction without affecting the switch.

A further object of this invention is to provide a push-button multiple switch structure embodying a rotary contact carrier with wipers engaging the carrier, and also embodying an improved means including a pawl and ratchet for progressively rotating the carrier.

With the above and other objects in view, my invention consists in the arrangement, combination and details of construction disclosed in the drawings and specification, and then more particularly pointed out in the appended claim.

In the drawings:

Figure 1 is a plan view partly in section of a push-button multiple switch structure constructed according to an embodiment of this invention.

Figure 2 is a sectional view taken on the line 2—2 of Figure 1.

Figure 3 is a sectional view taken on the line 3—3 of Figure 2.

Figure 4 is a diagrammatic view showing the electric circuits associated with this switch structure.

Referring to the drawing, the numeral 10 designates generally a frame structure which is formed with a pair of upright plates 11 which are secured together by means of a connecting bar 12 and fastening members 13. The frame structure 10 includes a pair of laterally projecting bars 14 secured to the outer sides of the side members 11 by fastening means 15, and the bars 14 are adapted to be secured by fastening means 16 passing through the bars 14 to the base 17 of a lamp structure.

In the present instance the push-button multiple switch structure is disposed within the hollow base 17 which includes a top wall 18, a side wall

19, and a removable bottom wall 20. A contact carrier generally designated as 21 is rotatably disposed between the side members 11 and comprises a shaft 22 journaled between the side members 11 and having fixed thereto a pair of cylindrical insulating members 23 and 24.

A ratchet 25 is disposed between the inner ends of the cylindrical insulating members 23 and 24 and is fixed to the shaft 22. The insulating members 23 and 24 are formed with circumferentially spaced apart longitudinal grooves 26 and 27, respectively. The insulating member 23 has disposed in one groove 26 thereof a bridging contact 28 and insulating member 24 has disposed in an aligning groove 27 thereof a bridging contact 29. The contact 28 is disposed adjacent the inner portion of insulating member 23; whereas, contact 29 is disposed adjacent the outer end portion of insulating member 24.

A second bridging contact 30 is disposed in a second groove 26 of insulating member 23 being positioned adjacent the outer end portion of member 23. An aligning contact 31 is disposed in insulating member 24 adjacent the outer portion of this member. A third bridging contact 32 is disposed in another one of grooves 26 of insulating member 23 adjacent the outer portion of this member, and an associated aligning contact 33 is disposed in another one of the grooves 27 of insulating member 24 and is adjacent the inner portion of member 24. An inner pair of wipers 34 and 35 are fixed to an insulating bar 36 which is carried by the connecting bar 12. An intermediate pair of wipers 37 and 38 are also secured to the insulating bar 36 outwardly from the wipers 34 and 35, respectively, and are adapted to be connected to a source of electric current supply by means of conductors 39 and 40, respectively. An outer pair of wipers 41 and 42 are also fixed to the insulating pair 36 outwardly of the intermediate supply wipers 37 and 38.

Contact 30 is adapted upon rotation of carrier 21 to bridge the two wipers 37 and 41, and at this time contact 31 is in a bridging position across wipers 38 and 42. When carrier 21 is rotated to close a circuit to contacts 28 and 29, contact 28 will bridge wipers 34 and 37, and contact 29 will bridge wipers 38 and 42. When contacts 32 and 33 are in circuit closing position by rotation of carrier 21, contact 32 will bridge wipers 37 and 41, and contact 33 will bridge wipers 35 and 38.

Carrier 21 is rotated by means of a pawl 43

which is pivotally carried on a reduced intermediate portion 44 of a shaft 45. The shaft 45 is formed at the ends thereof with reduced diameter studs 46 which slidably engage through horizontally disposed elongated slots or guides 47 which are formed in the side members 11 of the frame 10. A pair of springs 48 are connected at one end thereof to the studs 46 and at the opposite ends thereof to laterally projecting pins 49 which are carried by the frame side members 11.

The springs 48 constantly urge the shaft 45 to move inwardly at which time the pawl 43 will idle or ratchet over the ratchet member 25. The shaft 45 is moved forwardly to rotate the carrier 21 by means of a pair of bellcrank levers 50 which are rockably mounted on a shaft 51 secured between the side members 11. The inner arms 52 of the bellcranks 50 project upwardly and bear against the inner side of the shaft 45, and the inner arms 52 are disposed on opposite sides of the pawl 43. The other arms 53 of the bellcranks 50 are inclined upwardly and are connected together by a connecting bar 54 which is secured to the arms 53 by fastening means 55.

The bellcrank lever structure 50 comprising the two bellcranks is adapted to be rocked downwardly by means of a vertically disposed pin or stud 56 which is slidable through a guide 57 carried by the base 17. The pin or stud 56 is preferably formed of insulating material which may be of any desired color, and the pin or stud 56 includes an annular flange 58 bearing against the lower end of the guide 57. The pairs of bridging contacts which are carried by the carrier 21 are circumferentially spaced apart so that when one pair of contacts is in bridging position and the carrier 21 is subsequently rotated by rocking of the bellcranks 50 through downward movement of the pin 56, the carrier will be disposed in a circuit breaking position with the several wipers engaging the carrier 21 between adjacent pairs of contacts. In this manner when the switch structure is connected to what is termed a three-way light bulb as diagrammatically shown in Figure 4 with one downward movement of pin 56, a circuit will be closed to one filament of a light bulb, and a second downward movement of pin 56 will cause the circuit to the first filament to be broken.

A second downward movement of pin 56 will close a second circuit to the light bulb, and a third downward movement of pin 56 will effect breaking of a second circuit.

5 What is claimed is:

A push-button multiple switch for multiple filament lamps or circuits comprising a frame formed of a pair of side members and connecting means secured between said side members, a contact carrier rotatably disposed between said side members, said carrier comprising a shaft, a pair of longitudinally spaced cylindrical insulating members fixed to said shaft, a plurality exceeding two of lengthwise extending and circumferentially spaced apart bridging contacts fixed in each cylindrical member, the contacts of one cylindrical member aligning with the contacts of the other cylindrical member, the space between adjacent pairs of contacts constituting circuit breaking means, a plurality in excess of two wipers carried by said frame an equal number engaging each insulating member each contact being of a length to bridge only an adjacent two wipers, a ratchet fixed to said shaft between said members, said frame having a pair of elongated openings a slide shaft carried by said frame and engaging in said openings, a pawl rockably carried by said slide shaft and engaging said ratchet, a pair of bellcranks, means rockably mounting said bellcranks in said frame whereby one leg of each bellcrank will engage the inner side of said slide shaft, springs constantly urging said slide shaft rearwardly, and push-button means extending out of said frame for rocking said bellcranks for moving said ratchet to rotate said carrier to juxtapose a selected pair of contacts to bridge selected pairs of wipers.
